UNITED STATES PATENT OFFICE.

HUGH S. SHANNON, OF DETROIT, MICHIGAN.

HAND-TRUCK.

1,322,633.

Specification of Letters Patent. Patented Nov. 25, 1919.

Application filed May 9, 1919. Serial No. 296,035.

To all whom it may concern:

Be it known that I, HUGH S. SHANNON, a subject of the King of England, at present residing at Detroit, Wayne county, Michigan, U. S. A., have invented certain new and useful Improvements in Hand-Trucks, of which the following is a specification.

In the use of trucks for moving heavy articles it is frequently advisable to be able 10 to load an article like a barrel upon the truck without having to lift it and it is also advisable to be able to move the truck into loading position without having to slide it upon the floor.

15 This invention relates to trucks and to an arrangement thereof whereby a user may by a minimum of effort load a barrel or like article upon the same without having to lift the article itself and without having to push 20 the truck which is usually quite heavy, into position, there being an arrangement whereby the truck is at all times in rolling contact with the floor.

The invention consists in matters herein- 25 after set forth and more particularly pointed out in the appended claims.

In the drawings:

Figure 1 is a view in front elevation of a truck that embodies features of the invention;

Fig. 2 is a view in longitudinal section;

Fig. 3 is a view in side elevation of the truck; and

Fig. 4 is a view slightly reduced showing 35 a method of securing a barrel thereon.

Referring to the drawings, a pair of longitudinal sills 1 which are extended to provide handles 2, are held in spaced relation by cross members 3 framed into the sills or 40 otherwise properly secured in position.

A pair of bearing wheels 4 on a shaft or axle 5 normally carry the truck. A toe plate 6 having the usual forwardly extending portion to underrun articles to be loaded on the truck, is secured across the end portions of the sills remote from the handles 2 and extends at substantially right angles to the plane of the members 2. Loading wheels 7 are each maintained on the end portions of 45 the sills 2 as in suitable brackets 8, in such relation to the toe plate 6 that when the truck is up-tilted into a substantially upright position, the loading wheels 7 permit the user to move the truck on these wheels and 50 thereby insert the toe plate under an article

like a barrel by merely tilting the latter forwardly from the truck slightly to permit the introduction of the toe plate beneath the article.

To maintain such a package, barrel, box 60 or bale in position, a hook 9 of suitable type is secured to a flexible member 10, such as cable or chain, which passes over a drum 11. Suitably rounded guides 12 are mounted 65 firmly by suitable means on each of the cross members 3 so that the rope or cable 10 may be passed through and around one at a suitable height to permit the hook 9 to drop over the chine of a barrel edge or box or engage in the covering of a bale. A ratchet 70 lever 13 in convenient reach of the truck user operates a ratchet wheel 15 to hold the drum 11 and a shaft 20 on which it is secured against the pull exerted by the engaged hook 9. A take up weight 16, which is reciprocatable on a rod 17 or guide arranged longitudinally of the truck, draws a rope or cable 18 which is wound around a cylinder 19 on the shaft 20 of the drum 11 in opposite direction to the cable 10 so that when the 80 hook 9 engages the bundle, bale, barrel or box, the weight automatically takes up the slack of the hook cable. The pawl 14 locks the shaft and ratchet 15 in adjusted position when the hook imposes a strain on the cable 85 10 to hold the article on the truck.

To release the article, the truck is up-tilted, the latch 13 pulled out toward the user thereby disengaging the pawl 14 from the detent wheel 15 and allowing the article, 90 bale, or barrel to settle down into position. When the hook is thus released, the weight 16 rolls up the cable of the hook on chain 11, leaving the truck in condition for further operation.

Obviously changes in the details of construction may be made without departing from the spirit of the invention and I do not care to limit myself to any particular form or arrangement of parts within the scope of 100 the appended claims.

I claim as my invention:

1. A loading truck comprising a frame of longitudinal sills secured in spaced relation by cross members, bearing wheels supporting one end of the frame, a toe-plate extending outwardly from this end, loading wheels on the frame adjacent to the toe-plate adjusted to support the truck when tilted up 105 from the bearing wheels, a drum journaled 110

on the truck, a flexible member winding around the drum and terminating in a hook adjusted to engage an article resting on the toe-plate, guiding means on the transverse members around one of which the flexible hook connection may be passed, and a take-up weight slidably longitudinally on the truck having a flexible connection with the drum for winding up the hook connection 10 when the hook is released.

2. A loading truck comprising a frame of longitudinal and cross members secured together, bearing wheels near one end thereof, a toe-plate extending outwardly from the bearing wheel end, loading wheels secured on the toe-plate end portion of the frame and adapted to carry the truck when tilted up from the bearing wheels, a drum rotatably mounted on the truck, a flexible connection wound around the drum, a hook secured thereto and adapted to engage an article resting on the toe-plate, bits on the cross members of the truck for guiding the flexible connection, a take-up weight slidably longitudinally on the truck and having a flexible connection with the drum for winding up the hook connection when the hook is released and the truck up-tilted, and manually operable means for locking the drum 20 and holding the hook in adjustable position.

3. A loading truck comprising a frame of longitudinal and cross members secured together, bearing wheels near one end thereof, a toe-plate extending outwardly from the bearing wheel end, loading wheels secured on the toe-plate end portions of the frame and adapted to carry the truck when tilted 30

up from the bearing wheels, a drum rotatably mounted on the truck, a hook having a flexible connection wound around the drum 40 and adapted to engage an article resting on the toe-plate, bits on the cross members of the truck for guiding the flexible connection, a take-up weight slidably longitudinally on the truck and having a flexible connection with the drum for winding up the hook connection when the hook is released and the truck up-tilted, a ratchet wheel secured to turn with the drum and a ratchet lever having a holding engagement with the 45 ratchet wheel, manually operable to release the wheel and drum. 50

4. A loading truck comprising a frame, bearing wheels normally supporting one end portion thereof, loading wheels adapted to carry the frame in upright position, a toe-plate extending forward from the frame adjacent to the loading wheels, a drum shaft journaled transversely on the frame, a drum thereon, a flexible connection wound around the drum and provided with a hook for engaging an article on the toe-plate, means on the frame for guiding the flexible connection through the frame, a guide secured longitudinally on the frame, a take-up weight reciprocatable on the guide, a sheave on the frame, a take-up cable passing around the sheave on the frame and winding around the drum oppositely to the hook connection, a ratchet wheel secured to the shaft and a 55 manually operable ratchet lever having locking connection with the ratchet wheel. 60 65 70

HUGH S. SHANNON.
